UNITED STATES PATENT OFFICE

2,260,533

LIFTING MECHANISM

Joseph J. Mizer, Racine, Wis., assignor to Walker Manufacturing Company of Wisconsin, Racine, Wis., a corporation of Wisconsin

Application May 6, 1940, Serial No. 333,457

5 Claims. (Cl. 254—133)

The present invention relates to vehicle lifting arrangements and, in particular, is directed to lifting arrangements of the type described and claimed in applicant's copending application, Serial No. 329,537, filed April 12, 1940, for reissue of United States Patent No. 2,168,489, and in applicant's Reissue Patent No. 21,560, granted September 10, 1940.

As pointed out in the above copending application, the problems of providing an inexpensive but readily applied and used vehicle lifting mechanism has been complicated in recent years by the tendency to deepen the skirt portions of vehicle fenders and to provide the vehicle bodies with substantially overhung portions at the front and rear ends.

In accordance with the construction of the copending application, it is proposed to provide a two-part jacking mechanism, one part being utilized to initially lift the vehicle, and the other part being utilized to hold the vehicle in elevated position. An important feature of applicant's constructions resides in the fact that the elevating member is applied to an exposed part of a vehicle wheel, which exposed part of the vehicle wheel is readily accessible from the side of the vehicle and affords a lifting point to which the jack can readily be applied.

In the broader aspect of applicant's invention, a vehicle wheel provides several usable loading points. For example, present day vehicle wheel structures comprise generally a hub portion and a rim portion. Customarily, the hub portion is formed as an outwardly presenting recess, and the outer portion of the rim is usually upwardly and outwardly curved so as to define a corresponding surface. In applicant's constructions, it is proposed, therefore, to provide the lifting device with a lifting lug or nose, which is so formed as to adapt it to seat beneath a projecting part of the wheel, which projecting part of the wheel may be constituted, for example, by either of the just mentioned loading surfaces.

The jack structures specifically disclosed in applicant's co-pending application are characterized in that the lifting lug which engages the projecting part of the wheel is carried by and movable with a column, which column is supported in a jack body, and which jack body, in turn, is fixedly supported relative to a base in such relation that the column and the head extend upwardly therefrom at a slight inclination towards the wheel. The jack is provided with the usual elevating means, operable to cause the

column and the head to be elevated relative to the base.

It has been found, in the practical development of the structures of the co-pending application, that it is possible to take advantage of the above described loading points on the exposed surface of the wheel without requiring a jack of the just mentioned type. Instead, it has been found practical to practice the invention by employing a jack comprising simply a base, a column, and a lifting head which can be elevated relative to the column. Such latter structures can be manufactured at a substantially lower cost than the jack structures of the copending application.

With the above as well as other considerations in view, the principal objects of the present invention are, therefore, to provide a vehicle lifting arrangement characterizable as comprising the combination with a particular exposed outer part of a vehicle wheel, of a jack structure having a head engageable with such part of the wheel, and which part constitutes the sole loading connection between the wheel and the jack; to provide an improved jack structure adaptable for use in the just mentioned combination, and characterized as comprising a lifting head, a column for supporting the lifting head, means for elevating the head relative to the column, and a supporting base for the jack characterized as effective to prevent substantial rotative movement of the column but as also permitting a limited amount of universal tilting movement of the column relative to the base.

With the above as well as other objects in view, which appear in the following description and in the appended claims a preferred but illustrative embodiment of the invention is shown in the accompanying drawings, throughout the several views of which corresponding reference characters are used to designate corresponding parts and in which:

Figure 1 is a view in side elevation of an arrangement embodying the invention;

Fig. 2 is a view taken along the line 2—2 of Fig. 1;

Fig. 3 is a view taken along the line 3—3 of Fig. 2;

Fig. 4 is a detailed view, taken along the line 4—4 of Fig. 2;

Fig. 5 is a view of a modified embodiment of the invention;

Fig. 6 is a detailed view taken along the line 6—6 of Fig. 5;

Fig. 7 is a view of a further embodiment of the invention; and,

Fig. 8 is a detailed view, taken along the line 8—8 of Fig. 7.

Referring first to the embodiment of Figs. 1 through 4, the improved jack 10 is illustrated as applied to the wheel 12 of an illustrative vehicle 14, the fender 16 whereof is in accordance with conventional practice, relatively deeply skirted. The wheel 12 is carried by an unsprung part of the vehicle body, and it will be appreciated that by applying the jack 10 to the wheel the jack is required to be elevated only an amount approximately equal to the inflated diameter of the tire 20 associated with the wheel 12. It will be understood that, as is set forth in the above identified copending application, the vehicle is also preferably provided with a holding column or the like (not shown) which can be seated beneath an unsprung part of the vehicle after the same has been lifted by the jack 10, so as to hold the vehicle in elevated position. This permits the jack 10 to be removed, after which the tire or wheel or both may be changed as desired.

As most clearly appears in Fig. 2, the wheel 12 is of generally conventional construction, comprising the hub portion 22 formed as an outwardly presenting recess, the web 24, shown as formed integrally with the hub structure; and the rim 26, the inner surface of which is seated upon and rigidly secured to the web 24. The rim 26 is conventionally formed to afford a seat for the tire 20, and it will be noted that the rim is provided with a curved portion 28 which portion is upwardly and outwardly curved in a plane which includes the axis of the wheel 12, and which portion 28 is utilized, in the embodiment now being described, as the wheel loading point. In certain of the appended claims, the areas 22 and 28 are generically referred to by the term "outwardly presenting recess."

The jack 10 comprises the substantially linear, rigid column 30, generally rectangular in form, and illustrated as having usual ratchet teeth 32 provided along one face thereof. The column 30 carries a head 34, having a rim engaging lug 36 at one side thereof, and is formed to accommodate usual lifting elements (not shown), so arranged that by manipulating the handle 38, the head 34 may be elevated or lowered relatively to the column 30. The head 34 is provided with the usual setting lever 40, so as to control the direction of the movement of the head, as will be understood.

In the present instance, the column 30 is carried by a base 42, which may be, and preferably is, formed of a relatively heavy metal stamping, the base portion whereof is of sufficiently large area to afford a firm support for the column 30 and which is provided with a boss formation 44. The boss formation 44 is depressed in its central portion 46, to define a generally rectangular seat for the column 30, which seat relatively loosely receives the lower end of the column 30. With this relation, the seat 46 is effective to prevent any substantial amount of rotative movement of the column 30 about its own axis, and at the same time, permits the column 30 to be tilted universally relative to the base 42. The seat 46 is positioned relatively near the front face 48 of the base, since this disposition enables the lower end of the column 30 to be placed nearer the outer face 20a of the tire 20 than would otherwise be possible.

The lifting lug 36 is constituted by a relatively heavy metal strap, folded into generally U-shape, with the ends thereof rigidly secured to

the front face of the head 34. In accordance with the arrangement claimed in applicant's above-identified Reissue Patent No. 21,560, the lug 36 is formed to define an elongated rounded body portion 50, the curvature of which portion, in a plane which includes the axis of the wheel, corresponds to the radius of curvature of the loading portion 28. The curvature of the body portion 50, in a plane generally parallel to the plane of rotation of the wheel, is preferably proportioned in accordance with the radius of the rim 26, which latter curvature is most clearly shown in Fig. 3. With this relation, the rounded elongated body portion of the lifting lug 36 interlocks beneath the loading point 28.

A feature of the present arrangement resides in the fact that the rounded body of the lifting lug 36 lies immediately adjacent to but slightly spaced from the axis of the column 30. Two considerations determine this laterally offset spacing: first, it is desirable to maintain the offset at as low a value as is possible, so as to reduce the value of the turning moment which would otherwise be applied to the column 30 by means of the wheel; second, it is necessary to utilize a large enough offset to permit the upper end of the column 30 to clear the outer wall of the tire 20.

It will be appreciated that when the present jack is applied to a wheel having a deflated tire, the base 42 of the jack must be positioned somewhat farther outwardly from the rim than is the case with the upper end of the jack. Accordingly, in applying the present jack to a wheel, it is necessary that the column 30 extend upwardly at a slight inclination to the vertical. This inclined relation is permitted by the loose or universal mounting between the column 30 and the base 42.

In seating the jack adjacent the wheel, it will further be understood that the upper end of the column is projected into the space between the fender skirt and the wheel. As previously mentioned, also, the offset relation of the lifting lug is such that with the column in the just-mentioned slightly inclined position, the lifting lug can be brought into interlocking relation with the surface 28 of the rim. By operating the handle 38, accordingly, the head 34 and the lug 36 may be elevated to correspondingly elevate the wheel.

It will be understood that in manipulating the handle, the operator may tend to rock the jack about the axis of the column 10. Any such rotation is prevented or limited to a negligible degree by the fact that the column 10 is substantially non-rotatable relative to the base and by the further fact that the head 34 is non-rotative relative to the column. Moreover, the elongated form of the lifting lug enables the lug to have a substantial bearing along the rim, which further overcomes any otherwise existing tendency for the lug to become unseated from the rim.

It will be understood that during the upward movement of the wheel, the wheel moves about a center constituted by the point at which the opposite wheel rests upon the ground. During this arcuate movement, the wheel tends to move away from the base of the jack. Any such movement is accommodated in the present instance by the fact that the jack column can tilt relative to the base.

It is found in practice that after a user of a jack has changed the tire or wheel, as the case

may be, and has again elevated the wheel so as to enable him to remove the holding column (not shown), such user frequently rolls the car off the jack, rather than lowering the jack. In rolling the car off the jack, the jack column is necessarily tilted in the direction in which the car is rolled, and in the absence of a tiltable connection between the column and the base, the base is necessarily subjected to a substantial bending force. This difficulty is entirely overcome with the present arrangement, since the column can tilt relative to the base, both forwardly and rearwardly of the vehicle.

In its broader aspects, the present invention also admits to the use of a jack structure of the type shown in Figs. 5 and 6, wherein the jack 10a comprises a column 30a, and a head 34a, related to each other in the previously described manner. In this instance, also, it will be understood that the column 10a is provided with a base (not shown) corresponding to the previously described base 42. In this instance, however, the head 34 is provided with a lifting lug 60, of upwardly presenting saddle form, adapted to seat beneath the outwardly projecting axle spindle 62 associated with the wheel 12a. With the exception of the fact that the lifting lug 60 is in this case applied to the wheel spindle rather than to the rim portion, the construction and operation of the embodiment of Figs. 5 and 6 may, and preferably does, correspond to that of Figs. 1, 2, 3 and 4.

As previously mentioned in connection with the descriptions of Figs. 1 through 4, the hub structure of a vehicle wheel is conventionally formed as a generally outwardly presenting recess, having the outwardly flaring walls 22b, as shown in Fig. 7. In the broader aspects of the invention, there are certain instances in which it is found practical to apply a jack structure directly to the outwardly projecting and flaring surface 22a. Normally, however, such surfaces present a too steeply rising angle. Accordingly, a feature of the present invention resides in depressing into such hub opening, a circumferentially extending recess 80, the inner face whereof defines a loading point similar in form to the loading point 28 described with reference to Figs. 1 through 4. In such instances, a jack structure of the specific form described with reference to Figs. 1 through 4 may be utilized, and such jack structure is so shown in Figs. 7 and 8, the only difference being that in Figs. 7 and 8, the curvature of the lifting lug 82 in a plane parallel to the plane of rotation to the wheel is struck on a shorter radius, corresponding to the radius of the area 80.

Although only three specific embodiments of the invention have been described in detail, it will be appreciated that further variations in form and arrangement may be made within the spirit and scope of the invention.

What is claimed is:

1. A lifting device for a vehicle wheel, said wheel having an outwardly projecting part associated therewith, comprising a base adapted to rest upon a supporting surface, a column carried by the base and extending upwardly therefrom, the column being tiltable but substantially non-rotative about its longitudinal axis relative to the base, a head carried by the column, said head having a lifting part immediately adjacent the axis of the column but offset therefrom and formed to hook beneath said projecting part, said base, column and head being so related to

each other that when said base is positioned on said supporting surface immediately adjacent the base of a tire associated with said wheel said lifting part engages under and in lifting relation to said projecting part, and means operatively associated with said lifting device for raising said head relative to the column so as to lift said wheel.

2. A lifting device for a load carrying vehicle wheel having a tire and means including a rim-like part forming a seat for said tire, said part having an exposed surface which extends outwardly in a plane which includes the wheel axis, comprising a base adapted to rest upon a supporting surface, a column carried by the base and extending upwardly therefrom, the column being tiltable but substantially non-rotative about its longitudinal axis relative to the base, a head carried by the column, said head having a lifting part immediately adjacent the axis of the column but offset therefrom and formed to hook beneath said exposed surface, said base, column and head being so related to each other that when said base is positioned on said supporting surface immediately adjacent the base of a tire associated with said wheel said lifting part engages under and in lifting relation to said exposed surface, and means operatively associated with said lifting device for raising said head relative to the column so as to lift said wheel.

3. A lifting device for a load carrying vehicle wheel having an outwardly projecting spindle, comprising a base adapted to rest upon a supporting surface, a column carried by the base and extending upwardly therefrom, the column being tiltable but substantially non-rotative about its longitudinal axis relative to the base, a head carried by the column, said head having an upwardly presenting saddle positioned immediately adjacent the axis of the column but offset therefrom and formed to seat beneath said spindle, said base, column and head being so related to each other that when said base is positioned on said surface immediately adjacent the base of a tire associated with said wheel said saddle engages under and in lifting relation to said spindle, and means operatively associated with said lifting device for raising said head relative to the column so as to lift said wheel.

4. A lifting device for a vehicle wheel having in the outer face thereof a recess which is substantially concentric with the wheel and the marginal surface whereof extends outwardly toward the outer face of the wheel, comprising a base adapted to rest upon a supporting surface, a substantially linear column carried by the base and extending upwardly therefrom, the column being tiltable but substantially non-rotative about its longitudinal axis relative to the base, a head carried by the column, said head having a lifting part immediately adjacent the axis of the column but offset therefrom and formed to operatively engage under the said marginal surface at a point substantially directly above the wheel axis, said base, column and head being so related to each other that when said base is positioned on said supporting surface immediately adjacent the base of a tire associated with said wheel and said lifting part is engaged under said marginal surface said column extends inclinedly towards said wheel from said base, and means operatively associated with said lifting device for raising said head relative to the column so as to lift said wheel.

5. A lifting device for a vehicle wheel, said wheel having an outwardly projecting part associated therewith, comprising a base adapted to rest upon a supporting surface, a column carried by the base and extending upwardly therefrom, a head carried by the column, said head having a lifting part immediately adjacent the axis of the column but offset therefrom and operative to hook beneath said projecting part, said lifting part having an elongated body which extends generally parallel to the plane of rotation

of the wheel and the engaging surface whereof is arcuate in said plane, said base, column and head being so related to each other that when said base is positioned on said supporting surface immediately adjacent the base of a tire associated with said wheel said lifting part engages under and in lifting relation to said projecting part, and means carried by and operatively associated with said head for raising said head relative to the column so as to lift said wheel.
